UNITED STATES PATENT OFFICE.

SAMUEL STORCH AND HYMAN GELLMAN, OF NEW YORK, N. Y.

SAFETY KEY-HOLDER.

1,304,403.

Specification of Letters Patent. Patented May 20, 1919.

Application filed January 6, 1919. Serial No. 269,736.

To all whom it may concern:

Be it known that I, SAMUEL STORCH, and that I, HYMAN GELLMAN, citizens of the United States, residing at New York city, 5 in the county and State of New York, have invented jointly certain new and useful Improvements in Safety Key-Holders, of which the following is a full, clear, and exact specification.

10 This invention relates to safety key holders and has for its object to provide a device of that kind that will cost less to produce, and be more positive as a safety key holder.

Another object is to insure by a simple 15 and positive means, two very important objects, namely: that of securing a key holder to a garment, and also providing a means that will prevent the loss of a key, by accident, or otherwise, from a safety key holder.

20 With these and other objects in view, the invention consists in the construction and novel combination of parts hereinafter fully described, illustrated in the accompanying drawings and pointed out in the claims 25 hereto appended; it being understood that various changes in the form, proportion, size and minor details of construction, within the scope of the claims, may be resorted to without departing from the spirit or sacrificing any of the advantages of the invention.

In the drawings:—

Figure 1, is a sectional view of a safety key holder constructed in accordance with 35 this invention, said view being taken on line 1—1 of Fig. 2.

Fig. 2, is a plan view of same showing how a key ring is held in same.

Fig. 3, is a section taken on line 3—3 of 40 Fig. 4.

Fig. 4, is a plan view of same showing a key ring supported in same.

Fig. 5, is a fragmental portion of the lower return bend of Figs. 1 and 3, showing 45 the cut out portion through which the locking member passes and rests.

Fig. 6, is an elevation or face view of the locking member and

50 Fig. 7, is a side view of same in elevation. Like numerals of reference designate corresponding parts in all the figures of the drawings.

In the accompanying drawings, in which are illustrated the preferred embodiments of 55 the invention, 1, designates a key ring, mounted in the jaw of the upper return

bend or snap fastener and holder 2, and which is also equipped with a flat steel spring piece 3, which passes through an aperture 4, in the body portion of the device 60 as shown, and continues along the under side of said body portion to the lower return bend 5, of same, then conforms to inside curve of said bend, and ends at a convenient distance therefrom, substantially as 65 shown at 6, Fig. 1, and where it will serve for another purpose hereinafter explained. To insure a proper retention of said spring 3, same is held into a proper and pre-determined position as shown by suitable rivets 70 7 and 8, and which rivets facilitate the objects obtained therefrom. When not in service, the lower portion or return 9, of said spring piece 3, lies against the return portion of 5, of the body portion 10, as 75 shown in Fig. 1. In this lower return bend there is an aperture 11, and at a suitable distance depressions 12, 13, Fig. 4, are made on the inner edges of the aperture 11, sufficiently deep to receive and support the trunnions 14, 15 of the locking member 16, shown in Figs. 6 and 7.

In operation a key ring 1, such for instance as is shown in Figs. 2, 3 and 4, is pressed against spring 3, which yields inwardly for its admittance into the upper jaw as shown, and closes for its security instantly, and moreover insures the retention of a key ring, or a key ring and its contents, from dislodgment, then the return end portion 50, as shown in Figs. 1 and 3, is placed over the edge of a garment and the locking member shown throughout the several views is pressed into the position shown in Fig. 3. This causes the lower return end 6 of spring 90 3, to comply with the position shown in Fig. 3, and to securely bind or grip the goods which it engages, and which assures safety and moreover assures as is above stated, a safety key holder.

It will be understood that we make no claim upon the locking member 16, or the depressions 12 in which the trunnions 14 and 15 rest, and it is not thought necessary beyond the drawings to more specifically 105 point out its operation.

Having thus described our invention, what we claim as new and desire to secure by Letters Patent of the United States is:—

1. In a safety key holder, the combination 110 with a rigid strip having its end portions bent in opposite directions to overlap oppo-

site surfaces of the intermediate portion of the strip, there being a slot in said intermediate portion of the strip, of a spring strip having its intermediate portion secured to the intermediate portion of the rigid strip, one end portion of the spring strip extending through said slot and coöperating with one bent end portion of the rigid strip to form a snap hook for holding a key ring, the other end portion of the spring strip conforming to the other bent end portion of the rigid strip, and means carried by said last mentioned end portion of the rigid strip for actuating said last mentioned end portion of the spring strip to form a garment clasp between it and the intermediate portions of said strips.

2. In a safety key holder, the combination with a rigid strip having its end portions bent in opposite directions to overlap the opposite surfaces of the intermediate portion of the strip, of a spring tongue secured to said intermediate portion of the strip and coöperating with one bent end portion of the same to form a snap hook for holding a key ring, a spring member also secured to the intermediate portion of the strip and

conforming to the other bent end portion of the strip on the inner face thereof, and means carried by said last mentioned end portion of the strip for actuating said spring member to form a garment clasp between it and the intermediate portion of the strip.

3. In a safety key holder, the combination with a rigid strip having its end portions bent in opposite directions to overlap the intermediate portion of the strip, of a spring strip having its intermediate portion secured to the intermediate portion of the rigid strip, one end portion of the spring strip coöperating with one bent end portion of the rigid strip to form a snap hook for holding a key ring, the other end portion of the spring strip conforming to the other bent end portion of the rigid strip, and means carried by said last mentioned end portion of the rigid strip for actuating said last mentioned end portion of the spring strip to form a garment clasp between it and the intermediate portions of said strips.

In testimony whereof we have signed our names to this specification.

SAMUEL STORCH.
HYMAN GELLMAN.
